UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,123,579.

Specification of Letters Patent.

Patented Jan. 5, 1915.

Application filed March 11, 1908. Serial No. 420,409.

To all whom it may concern:

Be it known that I, LANSING ONDERDONK, a citizen of the United States, residing at New York, in the county of New York, 5 State of New York, have invented certain new and useful Improvements in Looper-Operating Mechanism for Sewing-Machines, of which the following is a description, reference being had to the accompanying drawing, and to the letters and figures of reference marked thereon.

My invention relates to sewing machines, and more especially to sewing machines operating to make a double thread chain stitch, 15 although from certain aspects, it will be obvious that my invention is also adapted to machines of other types.

The object of my invention is to improve the looper operating mechanism, whereby 20 the looper may be moved forward quickly with a short stroke substantially in a right line, then moved laterally quickly substantially in a right line, to give thereto a substantial avoiding movement and the looper is then 25 retracted substantially in a right line and subsequently quickly brought to the first position for its forward movement.

A further object of my invention is to provide a looper carrier so constructed that 30 the looper may be swung from normal position to a position where the same is accessible for threading.

Further objects of my invention will in part be obvious and will in part be herein- 35 after more fully described.

In the drawings which show by way of illustration one embodiment of my invention, Figure 1 is a front end elevation with parts in section, showing a sewing machine 40 with my improved looper mechanism applied thereto. Fig. 2 is a similar detail view showing the looper thrown forward for threading and the cover plate moved forward so that access to the looper may be 45 had. Fig. 3 is a longitudinal sectional view through the work support showing the looper operating mechanism as viewed from the rear of the machine and showing a portion of the needle bar and the needles carried thereby. Fig. 4 is a bottom plan view 50 of the looper operating mechanism. Fig. 5 is a detail view showing the connection between the main shaft and the looper operating mechanism, beneath the work sup-

port. Fig. 6 is a detail view partly in section, showing the looper operating mechanism as viewed from the rear of the machine. Fig. 7 is a similar view, showing the parts in a different position. Fig. 8 is a detail view partly in section, showing the 60 needles and loopers as viewed from the front of the machine, as the looper is moved forward into the needle loop. Fig. 9 is a similar view showing the loopers as being retracted. Fig. 10 is a detail view showing 65 in dotted lines the path of the eye of the looper relative to the needle and the spreader for the looper thread. Fig. 11 is a view showing the looper thread carried around the spreader and the needle entering between the looper thread and the body of the looper. Fig. 12 is a detail showing an 70 enlarged view of the spreader.

The work support 1 has rising therefrom, the usual overhanging arm which supports 75 at its forward end, the needle head 2. In said needle head 2, is mounted a needle bar 3, which reciprocates in a bearing 4 formed at the lower end of the needle head, and a second bearing 5 carried by the overhanging arm. Said bearing 5 as shown in Fig. 1, is located below the main shaft 6 and is spaced from the lower bearing 4 a distance only sufficient to allow the collar 7 in the needle bar, to receive a full reciprocation 80 from the main shaft 6. The collar 7 is connected to a crank disk 8, carried by the main shaft 6 through a link 9. The needle bar 3, extends above the bearing 5 only such a distance that when the needle bar is vibrated, it will not leave said bearing 5. It will thus be seen that my needle bar is extremely short and with the bearings 4 and 5 close together better overcomes the lateral action of the operating link 9, thus permitting 90 the use of a needle bar of small diameter, consequently of much lighter weight than is commonly used in sewing machines, which is very desirable in high speed machines.

The bearing 5 which supports the needle bar directly above the attachment of the link to said needle bar, supports the needle bar against the lateral thrusts of the link 9, and overcomes the tendency of the needle bar to 100 bind in its bearing also to wear the bearing hole oblong, as is liable when only one bearing is used. The presser bar 10, is of the

usual construction and carries a presser foot 11 at the lower end. Said presser bar is raised and lowered by the usual hand lever 12. The feed dog 13 is also of the usual 5 construction and will not need further description in order to make clear the invention forming the subject matter of this application.

A looper supporting shaft 14 is provided 10 with a looper carrier 15 or when desired, with a plurality of looper carriers, arranged side by side as shown in Figs. 3, 8 and 9. The looper carrier is rigidly secured to said shaft by a set screw 16. Said looper carrier 15 is made in two parts. The part attached to the looper supporting shaft 14 is provided with spaced ears 17, 17, see Fig. 8, between which the upper portion 18 of the carrier is pivoted by a suitable screw 19.

20 A spring 20 secured to the looper carrier engages the lower end 21 of the upper portion 18 of the looper carrier and normally holds said portion 18 with the looper in its extreme rearward position as shown 25 in Fig. 1. When, however, it is desired to thread the looper, the portion 18 of the carrier, may be tilted forward as clearly shown in Fig. 2 of the drawing. Said spring 20 is formed with a shoulder 20^a 30 which bears against the lower end of the upper portion and said shoulder operates to hold said upper portion either in its normal position or in its forward position for threading.

35 The looper 22 which is mounted in the looper carrier 15 as shown in the present illustration of my invention, is a thread carrying looper. It will be obvious from certain aspects of my invention, in place of 40 a thread carrying looper, a non-thread carrying looper may be used.

When the looper carrier 18 is tilted forward as shown in Fig. 2, the eye 23 of the looper 22 and the thread guide 24 of said 45 looper, are brought to a position underneath the opening 25 in the work support, which opening is closed by the usual sliding cover 26. It will thus be seen that the looper may be readily tilted forward so as to bring the 50 same underneath the opening in the work support for convenience in threading, after which said looper is returned to its normal position for operation.

Cooperating with the looper 22 is a 55 thread carrying needle 27 which is mounted on the lower end of the needle bar 3. If a plurality of loopers are used, then of course, a plurality of needles will be used, so that each looper will have coöperating 60 therewith a needle.

The looper supporting shaft 14 is mounted in bearings 28, 29 and 30 so that said shaft may not only oscillate, but be moved longitudinally. As a means for oscillating 65 said looper supporting shaft, I have pro-

vided the end of said shaft with a crank arm 31 which is connected by means of a link 32 to a rock lever 33, which is fulcrumed on a swinging link 34, pivoted at one end to the standard of the machine. 70 Said link is supported and vibrated up and down by means of an eccentric strap 35 which coöperates with an eccentric 36 on the main shaft 6. The rock lever 33 is oscillated from a pitman 37 which coöperates 75 with an eccentric 38 on the main shaft and is connected to the arm 33' of said rock lever.

The eccentrics 36 and 38 are oppositely disposed upon the shaft so that as the eccentric strap 35 moves in one direction, the eccentric strap 37 moves in the opposite direction. The link 32 and the downwardly extending arm of the rock lever 33, are so disposed that the pivotal connection 39 between said parts moves toward and from a line passing through the ball stud 40 on the arm 21 and the fulcrum 41 of the rock lever. It will be apparent therefore, that as the pivot stud 39 approaches said line, the 90 movement imparted to the looper supporting shaft will decrease until said movement is brought to a dwell. Said pivotal connection as shown in Fig. 5, moves slightly to the right of the line above referred to and therefore, the looper supporting shaft will be maintained at a dwell so far as its oscillating movement is concerned, 95 for a considerable period of time.

It will be apparent from the arrangement of parts shown in Fig. 5, that as the lever 33 swings from the dotted position to the position shown in full lines, the fulcrum point of said lever will be lowered as the swinging arm 34 which supports said 100 lever is also lowered by reason of the fact that the eccentric strap 35 is moved to its lowest position. The throw of the eccentrics 36 and 38 will therefore, be added together and give to the looper an extremely 105 quick forward movement. The looper is reaching the forward end of its stroke just as the pivot point 39 between the lever 33 and the link 32 has reached the center line above referred to, and therefore, the looper 110 will be caused to dwell a considerable length of time at the forward end of its stroke.

As the lever 33 moves from the position shown in full lines in Fig. 5, to the position shown in dotted lines, the looper is retracted. Again the throw of the eccentric 36 is added to the throw of the eccentric 38 and the looper will be brought very quickly to the rear end of its stroke and a slight 125 dwell will be caused in the movement of the looper owing to the fact that the eccentrics 36 and 38 are at this time passing the dead center. The swinging arm connection for supporting the rock lever and the arrange- 130

Having thus particularly described my invention, what I claim as new and desire to secure by Letters Patent, is:—

1. The combination of a main shaft, of a looper, a looper support, oppositely disposed eccentrics carried by the main shaft, means interposed between said oppositely disposed eccentrics and the looper support for moving the looper into and out of the needle loop, said means including devices for giving a dwell to the looper at the forward end of its stroke, an eccentric on the main shaft, and means interposed between said last named eccentric and the looper support for moving said looper laterally, said last named means including toggle links so disposed relative to their connection with the looper support as to move the looper laterally at each end of its stroke and to give to said looper a lateral dwell while said looper is moving into and out of the needle loop. 70
2. The combination with a looper, a looper support, means for oscillating said looper and means for moving said looper laterally including toggle links so disposed as to hold said looper from lateral movement during substantially its forward movement, and its backward movement, and move the same laterally at each end of its stroke. 90
3. The combination with a looper, a looper supporting shaft, means for oscillating said looper supporting shaft, including a main shaft, eccentrics oppositely disposed thereon and means intermediate said oppositely disposed eccentrics and said looper supporting shaft, including toggle links whereby the movement of said eccentrics is compounded, and transformed into a differential movement by said toggle links. 100
4. The combination of a work support, a looper shaft extending longitudinally of the work support, a looper mounted on said looper shaft, an arm projecting from said looper shaft, means for oscillating said looper shaft, comprising oppositely disposed eccentrics, a rock lever, one of said eccentrics being connected to said rock lever, a movable support for said rock lever, the other eccentric being connected to said support for moving the same, and means for connecting the rock shaft to the arm projecting from the looper shaft. 110
5. The combination of a work support, a looper shaft extending longitudinally of the work support, a looper mounted on said looper shaft, an arm projecting from said looper shaft, means for oscillating said looper shaft comprising oppositely disposed eccentrics, a rock lever, one of said eccentrics being connected to said rock lever, a movable support for said rock lever, the other eccentric being connected to said support for moving the same, and means for connecting the rock shaft longitudinally. comprising a lever, an eccentric on the main shaft, and connections between said eccentric and said lever. 120
6. The combination of a work support, a looper shaft extending longitudinally of the work support, a looper mounted on said looper shaft, an arm projecting from said looper shaft, means for oscillating said looper shaft, comprising oppositely disposed eccentrics, a rock lever, one of said eccentrics being connected to said rock lever, a movable support for said rock lever, the other eccentric being connected to said support for moving the same, and means for connecting the rock shaft to the arm projecting from the looper shaft, a third eccentric, a lever connected to said third eccentric, and a link for connecting said lever to said looper shaft for moving the same longitudinally. 130
7. The combination of a work support, a looper shaft extending longitudinally of the work support, a looper mounted on said looper shaft, an arm projecting from said looper shaft, means for oscillating said looper shaft, comprising oppositely disposed eccentrics, a rock lever, one of said eccentrics being connected to said rock lever, a movable support for said rock lever, the other eccentric being connected to said support for moving the same, and means for connecting the rock shaft to the arm projecting from the looper shaft, a third eccentric, a lever having a pivotal support in a horizontal plane passing through the longitudinal axis of the looper shaft, a link connecting one end of said lever to said third eccentric, and a link connecting the opposite end of said lever to said looper supporting shaft. 140
8. The combination with a looper, a looper supporting shaft, means for oscillating said looper supporting shaft and giving thereto a dwell, and means for moving the looper laterally, including a lever, a link connected to said lever and said looper shaft, the pivotal connection between said link and said lever moving in the same direction as the connection between the said link and said looper supporting shaft, whereby no lateral movement is given to said shaft during its oscillation, and the continued movement of said lever causes the shaft to move longitudinally during the dwell in the oscillating movements of said looper supporting shaft. 150
9. The combination of a looper, a looper supporting shaft, means for oscillating said looper, comprising oppositely disposed eccentrics, a rock lever, connections between one of said eccentrics and said rock lever, a swinging link supporting said rock lever, connections between the other eccentric and said link, means for connecting said rock lever to said looper supporting shaft, means for moving said looper supporting shaft longitudinally, comprising a lever, an eccentric on the main shaft, and connections between said eccentric and said lever. 160
10. The combination of a looper, a looper supporting shaft, means for oscillating said looper, comprising oppositely disposed eccentrics, a rock lever, connections between one of said eccentrics and said rock lever, a swinging link supporting said rock lever, connections between the other eccentric and said link, means for connecting said rock lever to said looper supporting shaft, means for moving said looper supporting shaft longitudinally, comprising a lever, an eccentric on the main shaft, and connections between said eccentric and said lever. 170

ment of the oppositely disposed eccentrics for operating the looper to give the same a quick forward and backward movement, is not of itself claimed herein, as the same forms the subject matter of my co-pending application #213,516, filed June 21, 1904. The combination however, of said swinging link, vibrating lever and oppositely disposed eccentrics with the link connection 32, whereby the looper is given an extended dwell at the forward end of its stroke, is a part of my present invention.

As a means for moving the looper supporting shaft longitudinally so as to give to the loopers the needle avoiding movement, I have provided said looper supporting shaft with a collar 42. Projecting from said collar 42 is a ball stud 43 (see Fig. 4). A lever 45 is pivoted at 46 upon the bearing 30. One end of said lever is connected by means of a link 47 to the ball stud 43. The other end of the lever 45 is provided with a ball stud 48, which is connected to a pitman 49 co-operating with an eccentric 50 on the main shaft 6.

As the lever 45 oscillates about its fulcrum 46, the pivotal connection 51 between said lever and the link 47 moves toward and from a line passing the fulcrum point 46 and the ball stud 43.

The operation of my looper is as follows:—As the looper supporting shaft 14 oscillates, the ball stud 43 carried thereby, will be oscillated about the axis of said looper shaft, moving from a position slightly above a horizontal plane passing through the axis of said shaft, as shown in Fig. 6 to a position slightly below said plane, as shown in Fig. 7. When the parts are in the position shown in Fig. 6, the looper has been moved laterally to avoid the needle and is about to be retracted. During the retracting of the looper, it is desirable to move the same so far as possible in a straight line, especially until the looper approaches very near to the rear end of its stroke. As the looper shaft 14 oscillates to retract the looper, the ball stud 43 moves from the position shown in Fig. 6 to the position shown in Fig. 7. The parts are so timed that as the ball stud 43 commences its oscillation, the pivotal point 51 between the link 47 and the lever 45 also moves downward and as the points 51 and 43 move downward together, there will be no longitudinal movement given to the looper supporting shaft, and consequently no lateral movement given to the looper. As soon however, as the looper approaches the rear end of its stroke, the movement of the pivotal connection 51 gains upon the oscillating movement of the stud 43, which is now slowed up by reason of the fact that the eccentrics 36 and 38 for operating the looper are approaching the dead center and as a consequence, the point

51 approaches a line passing through the fulcrum point 46 and pivot stud 43 and thereby causes a longitudinal movement of the looper supporting shaft 14.

As the pivot point crosses the line above referred to, the looper will be brought to a dwell so far as the lateral movement thereof is concerned. As the looper moves forward, the point 51 and the stud 43 will move upward together and no longitudinal movement will be given to the looper supporting shaft 14, until the looper practically reaches the forward end of its stroke, at which time the upward movement of the ball stud 43 ceases and the upward movement of the pivotal connection 51 continues and the looper will be moved very quickly, laterally and thus given its needle avoiding stroke. As the looper is reaching the forward end of its stroke, the link 32 and the rock lever 33 are approaching the position shown in full lines in Fig. 5, and the looper is therefore, brought to a dwell. The dwell of the looper at the forward end of its stroke continues practically during the entire time that the looper is moved laterally.

The resulting path of movement of the eye of the looper, is therefore as shown in Fig. 10, practically a right line movement forward into the needle loop, substantially a right line movement laterally to avoid the needle, a right line movement to withdraw the looper from the needle loop with a slightly rounded movement at the rear end of the stroke of the looper as the looper is brought to its normal position for movement forward into the needle loop.

On the under side of the throat plate, I have provided a loop spreader 52 which, as shown in the drawing, is in the form of a downwardly projecting post having a slightly inclined position see Fig. 12 to form a shoulder to receive the looper thread. This spreader (see Figs. 10, 11 and 12) is located directly in front of the needle. The looper moves forward into the needle loop, and when it reaches the forward end of its stroke, it is moved laterally to give thereto the needle avoiding movement. This lateral movement of the looper lays the looper thread on the shoulder 53 of the spreader, which shoulder is formed by the inclined position of the post as clearly shown in the drawings. As viewed in Fig. 2, the looper moves forward on the left of the spreader, and is retracted on the opposite side thereof. During the first part of the backward movement of the looper, the looper thread will be held on the spreader as shown in Fig. 11, which properly separates the looper thread from the body of the looper, so that the needle may enter between said looper thread and said looper body. A further backward movement of the looper will cause the looper thread to slip from the spreader.

centric on the main shaft, connections between said eccentric and said lever, and a projecting stud carried by said looper supporting shaft, and a link between said lever and said projecting stud.

10. The combination with a looper, a looper support, means for oscillating said looper and means for moving said looper laterally including toggle links so disposed 10 as to hold said looper from lateral movement during substantially its forward movement, and its backward movement, and move the same laterally at each end of its stroke, and a spreader arranged in the path of the 15 looper thread as the looper is moved laterally for engaging the same and separating the looper thread from the looper body for the entrance of the needle.
11. The combination of a work support, 20 feeding mechanism, a needle, a looper, a looper supporting shaft located substantially at right angles to the line of feed, a looper carrier mounted on said looper supporting shaft, said work support having an 25 opening formed therein, a cover plate for said opening, said looper carrier being formed of two parts, means for pivotally connecting said parts so that the part carrying the looper may be swung in a vertical 30 plane from its normal position beneath the opening in the work support, and render it easily accessible for threading.
12. The combination with a work support, 35 a looper supporting shaft mounted beneath said work support, a looper carrier thereon, a looper supported on said carrier, said work support having an opening therein, a cover plate therefor, said looper carrier being made in two parts whereby the same may 40 be moved forward from normal position beneath the opening in said work support, and a spring provided with means for holding said looper both in its normal position and in its forward position.
- 45 13. The combination of a looper carrier,

comprising two parts, one of which has spaced ears and the other of which is pivoted between said spaced ears and is provided with a downwardly projecting portion, a spring carried by one of said parts, 50 and having a shoulder therein which cooperates with the downwardly projecting portion of the carrier to hold said carrier in two predetermined positions.

14. The combination of a work support, 55 a looper, a looper support on which said looper is mounted, means for oscillating said looper support including oppositely disposed eccentrics, a swinging arm connected to one of said eccentrics, a rock shaft, 60 fulcrumed on said swinging arm and connected to the other eccentric, an arm carried by the looper shaft, and a link connecting said arm with the rock shaft, said link and said free arm of the rock shaft being disposed so as to be substantially in line when the looper is at one end of its stroke, whereby an increased dwell is given to the looper. 65

15. The combination of a work support, 70 a looper, a looper-supporting shaft, means for moving said looper-supporting shaft longitudinally, including a rock lever pivoted in a horizontal plane passing substantially through the axis of the looper shaft, an arm carried by the looper shaft and projecting laterally therefrom, a link connecting said arm and one end of said rock lever, the arm of said rock lever and said link being substantially in line when the looper shaft is at one end of its movement, means 75 for operating said rock lever, and means for oscillating the looper shaft to move the looper into and out of the needle loop.

In testimony whereof I affix my signature, in presence of two witnesses.

LANSING ONDERDONK.
